UNITED STATES PATENT OFFICE.

HENRY G. VOIGHT, OF NEW BRITAIN, AND ALBERT A. PAGE, OF EAST HAVEN, CONNECTICUT, ASSIGNORS TO SARGENT & COMPANY, OF NEW HAVEN, CONNECTICUT, A CORPORATION OF CONNECTICUT.

TRANSOM-OPERATOR.

1,306,291.

Specification of Letters Patent. Patented June 10, 1919.

Application filed October 13, 1916. Serial No. 125,363.

To all whom it may concern:

Be it known that we, HENRY G. VOIGHT, of New Britain, Hartford county, State of Connecticut, and ALBERT A. PAGE, of East Haven, New Haven county, State of Connecticut, have jointly invented certain new and useful Improvements in Transom-Operators, of which the following is a full, clear, and exact description.

10 This invention relates to transom operating devices, and it has particular reference to transom operators in which the main operating parts are within the door casing.

15 One of the primary objects of the invention is the provision of a transom operator of the concealed type, which is extremely simple in construction, and which can be produced at a very low cost.

20 Another object of the invention is to provide a device in which the transom can be very quickly adjusted to the desired position, and wherein the transom when once adjusted to that position will be very firmly held in place.

25 To these and other ends, the invention consists in the novel features and combinations of parts to be hereinafter described and claimed.

30 In the accompanying drawings, Figure 1 is a front elevation of a portion of a door frame and transom to which our improvements are applied;

35 Fig. 2 is a fragmentary front elevation on a larger scale, with certain parts broken away;

Figs. 3, 4 and 5 are side elevations of the parts shown in Fig. 2, showing the transom adjusted to different positions; and

40 Fig. 6 is an enlarged front elevation of the upper portion of the transom operator.

In the embodiment illustrated, the transom 10 of usual construction is located in the upper part of a door frame in the customary manner, and the transom operating means is housed for the most part in the door casing

45 11. This operating means includes a flat mounting plate 12, which may be conveniently attached to the inside of the door casing by screws 13, adjacent the upper portion

50 of the door opening. This plate is relatively short, extending from a point slightly above the lower edge of the transom to a point not very far below the lower edge of the transom. Near its upper end, the plate

12 carries a journal block 14 which serves as 55 a bearing for a rock shaft 15, by means of which the transom 10 is manipulated. This rock shaft extends through an opening in the plate 12 and through a sleeve 16 which is carried by the plate at the rear or under surface thereof and forms an additional bearing for the shaft. The sleeve is located in a suitable opening or cut away portion 17 of the door frame (Fig. 2), and the shaft extends through the frame and carries at its 60 inner end a crank or arm 18 secured to the edge of the transom. Preferably, the arm 18 is in the form of a flat plate mortised in the side edge of the transom at the lower part thereof, the lower end of said plate being near the lower edge of the transom, as shown by the dotted lines in Fig. 2. The arm or plate 18 is secured in the mortise in the transom edge by screws or other suitable fastening members 19. The inner end of the 65 shaft is suitably locked to the arm 18 and the shaft then inserted in the bearing in the mounting plate, after which said shaft is locked against lengthwise displacement in its bearing by a cotter pin 20 or the like at 70 its outer end.

75 It will be understood that by the construction described, the rock shaft forms in effect a swinging trunnion fixed to the transom and operating in an opening in the door 85 frame at one side of the transom. At the opposite side of the transom, the same is swingingly supported in the door frame by a plain trunnion and socket (in line with the rock shaft), which we have not considered it 90 necessary to illustrate. The rock shaft 15 and the transom carried thereby are operated by means of a depending swinging arm 21 mounted on the outer end of the rock shaft. In the particular embodiment shown, 95 the outer end of this shaft is of square cross-section and the upper end of the arm 21 has a square opening conforming to the square portion of the shaft beneath the cotter pin, so that the parts are effectively interlocked. The arm or crank 21 is actuated by mechanism mounted on the lower part of the plate 12. In the embodiment shown, this mechanism includes a bar 22 adapted to slide in a substantially vertical direction when actuated by a knob 23 or the like at the lower end thereof. The upper end of this bar or slide 22 is pivoted at 24 to a bell 100 105

crank or elbow lever 25 pivotally mounted on the base plate at 26. The pivot 26 is located at the elbow of this lever. At its other end, the lever 25 is pivoted at 27 to a short link 28 at one end of said link, the opposite end of said link being pivoted at 29 to the lower end of the operating arm 21 previously mentioned. The slide 22 is guided intermediate of its length by a cross piece or clip 30 applied to the face of the base plate, and at its lower end said slide is adapted to abut and rest against a stationary abutment 31 applied to the lower portion of the base plate. In the particular form shown, the lower end of the slide 22 is rounded off, and the abutment 31 is in the nature of a plate having a rounded cut away portion to conform to the lower end of the slide, and in which such lower end of the slide can be seated. A helical spring 32 is connected at one end to a post 33 on the lower part of the base plate, and at its upper end it is fastened to a post 34 on the slide 22. This spring urges the slide in a downward direction and normally holds its lower end in the seat afforded by the lower stop member 31.

At the lower end of the slide, the knob 23 is bodily connected therewith by means of a rigid knob shank 35 extending horizontally from the knob into a lateral projection 36 on the slide, in which projection the inner end of the knob spindle is rigidly secured by means of a pin or otherwise. The spindle 35 of the sliding knob extends through a slot 37 in the casing of the door frame, which permits the knob to have the necessary up and down movement. The casing is trimmed around the slot 37 by means of a suitable escutcheon 38, and the slot is closed at the rear of the casing member by means of a sliding plate 39, which has a square hole fitting over the square knob spindle so that said plate is carried along by the spindle in its up and down movement, said plate being sufficiently long to cover the slot at all times and being pressed against the inner face of the casing member by a spring 40 which holds the plate 39 yieldingly in position. The spring 40 is preferably of the helical type, embracing the knob spindle between the plate 39 and the projection 36.

The slide 22 is provided near its lower end with a series of notches 41, adapted to cooperate with a fixed stop 42 on the base plate, and above the uppermost notch 41 the slide is provided with a beveled surface 43 to coöperate with said stop.

When the parts are in the normal position, i. e., the closed position of the transom, the arm 21 hangs down nearly vertically, in line with the transom, and the pivots 29, 27, 26 of the lever mechanism or toggle mechanism connecting the arm 21 with the slide 22 are in line with each other transversely of the

plate 12, thereby providing a "dead center," which prevents the transom from swinging down out of its closed position and effectively locks it in that position. In other words, the link 28 and the elbow lever 25 interposed between the members 21 and 22 constitute a toggle lock for the transom. In this position, the lever 25 and link 28 are held against downward displacement beyond the locking position by means of a stop pin 25^a on the base plate. The toggle lock can, however, be broken or released by shifting the slide 22 upwardly through actuation of the sliding knob 23. As the knob is lifted from the position shown in Fig. 3, the slide 22 is raised in the clip 30. The inclined surface 43 coöperating with the stop 42 throws the lower end of the slide to the left with respect to Fig. 3, while the upper end is moved about the pivot 26 of the bell crank, so that the upper and lower ends of the slide are maintained in approximate vertical alignment at the same time that the slide shifts laterally in the clip 30 by virtue of its connection with the bell crank. As the upper end of the slide is raised, it pushes the bell crank into the position shown in Fig. 4, thereby breaking the toggle lock and shifting the transom to a slightly open position by actuation of the arm 21. If it is desired to open the transom only slightly, the knob 23 is released in the position shown in Fig. 4, so that the uppermost notch 41 will engage the stop 42, and thereby lock the parts in position. The spring 32 tends to hold the stop 42 engaged with the notch. If it is desired to open the transom to a greater extent, the knob is pulled forwardly from the position shown in Fig. 4, and then lifted so as to give the operating arm 21 and the transom a further swinging movement. When the transom has been opened to the desired extent, it can be locked in the adjusted position by engaging one of the notches 41 with the stop 42, as will be understood. When it is desired to close the transom again, the slide is moved out of engagement with the corresponding notch by pulling the knob outward to a slight extent, whereupon the spring 32 by carrying the slide downward will swing the transom back to the closed position. As this occurs, the knob moves downward to the lower end of its slot. A pin 44 on the upper portion of the base plate is engaged by the upper end of the slide to limit the upward movement of the latter. When the slide strikes this pin, the stop 42 is opposite the lowermost notch 41, so that on pushing the knob inward, after it has been raised to the limit of its movement, it will lock the transom in the position corresponding to the maximum opening.

Various changes may be made in the de-

tails of the construction, without departing from the scope of our invention as defined in the claims.

What we claim is:

- 5 1. In a transom operator, the combination of a base plate, a swinging operating arm having a swivel mounting in said base plate, a slide mounted on the face of said base plate to move in a substantially vertical direction,
- 10 10 a toggle connection between said slide and said operating arm positioned to have its knuckle moved to the dead center position as the transom reaches its closed position, whereby the transom is locked in the closed position, means for raising and lowering said slide, and a spring acting on the slide to normally hold the transom in the closed position.
- 15 2. In a transom operator, the combination of a base plate, a rock shaft journaled therein, an arm carried by said rock shaft and operatively secured thereto, an elbow lever mounted on said base plate, a link connecting said elbow lever with said arm and cooperating with said elbow lever to form a toggle, and means for operating said elbow lever, comprising a vertically movable slide; substantially as described.

3. In a transom operator, the combination of a base plate, a rock shaft journaled therein, an arm rigid on said shaft, a slide on the base plate for operating said arm, means for operating said slide, and a toggle lever connection between said slide and said arm comprising an elbow lever mounted on the base plate having one leg operatively connected to said slide and a link for connecting the other leg to said rigid arm; substantially as described.

4. In a transom operator, the combination of a transom, a crank operating lever rigidly secured to said transom, a longitudinally adjustable slide, and a toggle connection between said slide and said crank lever, said toggle having one of its arms pivotally secured to said crank arm and its other arm mounted upon a fixed pivot and constructed to have its toggle knuckle moved to the dead center position between said pivots as the transom reaches its closed position, whereby the transom is locked in its closed position.

In witness whereof we have hereunto set our hands on the 11th day of October, 1916.

HENRY G. VOIGHT.
